UNITED STATES PATENT OFFICE.

ALFRED MIDDLETON, OF LAVENDER BAY, NEAR SYDNEY, NEW SOUTH WALES,
AUSTRALIA.

COIN-ACTUATED LIQUID-DISPENSING MACHINE.

Application filed August 6, 1924, Serial No. 730,338, and in Australia August 29, 1923.

This invention has been specially devised in order to provide an improved coin actuated liquid dispensing machine of simple, effective and sanitary construction adapted for ready and effective cleansing and in which a supply of liquid is stored and may be kept at an even low or high temperature and be dispensed or discharged in predetermined quantities by an operable lever actuated by application of a coin thereto and which machine is specially suitable for use at schools and in buildings such as offices, factories and flats for dispensing milk in small quantities.

15   Briefly described, the invention comprises an insulated outer chest having a recess- or compartment therein for the reception of a receptacle or drinking cup; a separate container or tank adapted to be placed in the
20 outer chest and having a measuring chamber; a plate or bracket borne by the tank and supporting the actuating mechanism; and means observable from the exterior of the chest for indicating the amount of dispensable liquid remaining in the tank.
25   Other features of the invention, more or less ancillary to the foregoing, will be apparent as the description proceeds.

30 And in order that the invention and a practical application thereof will be readily understood the same will now be described with reference to the accompanying drawings in which:—

Figure 1 is a perspective view of the complete machine ready for use,

Figure 2 is showing the di in the bottom,

Figure 3 is a sectional elevation on the plane 3-3 in Figure 1.

Figure 4 is a longitudinal sectional elevation of the container or tank diametrically of the measuring chamber and looking to the far side whereon is affixed the actuating mechanism,

Figure 5 is an elevation of the supporting plate and actuating mechanism thereon as moved outwardly from the far side of the container, ...

50 Figure 6 is a partial sectional plan on the line 6-6 in Figure 4 showing the disposition of the measuring chamber, and

Figure 7 is a partial plan of the supporting bracket, brake and actuating lever.

55 The chest consists of box 11 upon legs 12

and a cover or closure 13 each constructed of dual walls 14 with insulating material 15 therebetween the cover having therethrough a coin slot 16 and an agitator handle slot 17 and the box having a sight slot 18 in one side, well or recess 19 in the bottom with a hole through its bottom for reception of a funnel 20 and thereunder an enclosure 21 with a spring closed door 22 at one side, a hole through the bottom for the drain pipe 23 of a tray 24 and a drip tank 25 removably securable about said bottom. The liquid container or tank carrying the measuring and actuating mechanism is removably housed in the chest and consists of container or tank 26 carrying hinged lifting loops 27 and having access opening 28 in the top with closure 29 therefor carrying an arm 30 hinged exteriorly as at 31 within a housing 32 on said closure and movable in slots 33 through said housing 32 and closure 29 and having on its outer end a handle 34 and on its inner end a blade or paddle 35 with which to agitate the contents of the tank. In the bottom of the tank is affixed an outlet junction 36 to which is removably secured the measuring and valve chamber consisting of wall 37, top 38, through pipe 39 with lower end formed as a valve seat 40, and a removable bottom 41 having discharge pipe 42 therefrom with upper end formed as a valve seat 43 and on its lower end a removable angular directing and protecting spout 44. Within the chamber and about the pipe 39 are annular hollow floats 45 of varying displacements and between the valve seats 40 and 43 a double faced valve 46 having a short shank on the upper face and from the lower face guide legs 47 in said pipe 42 and being adapted to seat upon either of the valve seats 40 and 43. Said valve 46 is connected by a chain 48 to the rod 49 which extends up through the pipe 39, the tank 26 and the top thereof and carries adjusting nut 50. Secured by suitable lugs and brackets to one side of the tank 26 and to the top of the measuring chamber is the supporting plate or bracket 51. Fulcrumed on an axle or trunnion 52 on said plate 51 is the actuating lever having on its short end 53 an adjusting balance weight 54 and near the fulcrum a lug 55 through and to which the end of the rod 49 is connected by nut 50, by which the operable length

is regulated so that the valve will be pulled upon the upper seat 40 at the termination of ascent of the short end of the actuating lever the chain 48 allowing for variations 5 in distances between the said end of the lever and the upper and lower positions of the valve 46. On the long end 56 of the lever is a counterbalanced pivoted coin tray 57 to receive a coin 58 directed thereinto 10 through a chute 59 to actuate the lever and in the path of the light end of the tray 57 is a counterweighted and upwardly checked trip 60 pivoted in a slotted bracket 61. On said plate 51 is a stop 62 to limit the 15 upward traverse of the long end 56 of the lever and on a trunnion 63 is a brake tumbler 64 counterbalanced as at 65 and having short and long lateral abutments or projections 66 and 67 and on the upper edge of 20 said lever is a lateral abutment 68 to be struck by the short projection 66 of the brake 64.

A glass pipe 69 is connected to the measuring chamber through orifice 70 therein and 25 is led up the outside of the tank 26 and into the side or top thereof so that a user may observe through the sight slot 18 in the chest whether there is any liquid in the machine before passing a coin thereinto and so that 30 air passing to or from the measuring chamber will be from or into the tank and not to or from the atmosphere and so prevent contamination.

In use the chest is opened, the tank 26 35 positioned therein, the actuating lever then being in its raised position and the valve 46 of the measuring chamber being upon the lower seat 43 and the floats 45 resting upon said valve. Liquid is then supplied 40 to the tank through its filling orifice 28, same is closed by closure 29 and the chest is closed and locked. Liquid flows through the pipe 39 into and fills the measuring chamber and raises the floats 45 thus freeing 45 the valve 46 so that upon a coin 58 being passed into the machine through the chute 59 it slides into the coin tray 57 upon the long end 56 of the lever and the added weight causes said end to descend and as it 50 approaches the limit of its descent its lower edge strikes the long projection 67 of the brake 64 causing the brake to rotate against the action of its weight 65 until the short projection 66 strikes the then upper side 55 of the lever projection 68 in order to check any rebound of said lever. As the other end 53 of said lever ascends the rod 49 and chain 48 lift the valve 46 from the lower seat 43 against the upper seat 40 thus permitting 60 liquid in the measuring chamber to discharge therefrom through the discharge pipe 42 spout 44 and the funnel 20 into a receptacle 71 placed under said funnel 20 and in the tray 24 in the discharge enclosure 21. While 65 the short end 53 of the lever is raised the

valve 46 is held with its shank in the pipe 39 and its upper face upon the upper seat 40 thus closing the pipe 39 and preventing further liquid from the tank 26 flowing into said chamber. As the liquid discharges 70 from the chamber the floats 45 therein descend and move the valve 46 towards the lower seat 43, the pipe 39 remaining practically closed until just before the valve reaches said seat, and descends the short 75 end 53 of the lever whose other end 56 is partially raised causing the coin tray 57 to pass the trip 60 and be tilted so that the coin 58 will be dislodged therefrom when the lever being freed of the added weight 80 of the coin rises to normal position and allows the valve 46 to close upon the lower seat 43 the pipe 39 remaining practically closed by the shank of the valve 46 to prevent liquid entering the measuring chamber 85 until the lower face of said valve reaches the seat 43. The chamber then refills with liquid and the operation may be repeated until the supply of liquid is exhausted which fact is ascertainable by inspection through 90 the observation slot 18 of the pipe 69.

The bottom 41 of the measuring chamber, the rod 49 and the valve 46 being removable provide for thorough cleansing also for the interchange of different sizes of floats 45 95 by which the quantity of liquid to be supplied at each operation of the machine is regulated.

I claim:—

1. In a liquid dispensing apparatus, a 100 chest having a pair of superimposed compartments separated by a substantially horizontally disposed partition having a central opening therethrough, a measuring chamber disposed in the upper compartment and having a valve port disposed substantially centrally above the said central opening, and a conduit leading laterally from the bottom of the valve port beyond the said central opening so as to form a baffle for preventing the said port discharging directly into the said central opening.

2. In a liquid dispensing apparatus, a tank having a discharge opening in its bottom; a hollow annulus disposed underneath the tank and having a central vertical through passage leading downward from the said discharge opening, and an annular chamber closed at the top and open at the bottom; a removable cover for the open bottom of the annulus having a central discharge opening disposed concentrically with relation to the said through passage, the lower end of the said passage being spaced from the said cover; a double-faced valve adapted to close alternately the lower end of the said passage and the discharge opening in the said cover and being, also, provided with a laterally extended flange; a float in the annular chamber adapted to rest on the said 115 120 125 130

flange; and valve lifting means rising from the said valve and through the said central passage into the said tank.

3. In a liquid dispensing apparatus, a holding tank, a measuring chamber having superimposed upper inlet and lower outlet ports, a valve intermediary of said ports and adapted for closing either one, a float adapted to rest on the valve when the chamber

is empty so that the valve closes the outlet port, means for lifting the valve to close the inlet port and open the outlet port, and means for arresting the descent of the valve after it has been lifted until the said float bears on the said valve. 10

Dated this third day of July, one thousand nine hundred and twenty-four. 15

ALFRED MIDDLETON.
